UNITED STATES PATENT OFFICE.

EMIL WEINHEIM, OF NEW YORK, N. Y.

METHOD OF PRODUCING A REINFORCED RESILIENT MATERIAL AND THE ARTICLE OF MANUFACTURE PRODUCED THEREBY.

1,267,025.

Specification of Letters Patent. Patented May 21, 1918.

Application filed February 16, 1916. Serial No. 78,624.

To all whom it may concern:

Be it known that I, EMIL WEINHEIM, a citizen of the United States, residing at New York city, in the county and State of New York, have invented a certain new and useful Improvement in Methods of Producing a Reinforced Resilient Material and the Articles of Manufacture Produced Thereby, of which the following is a specification.

Heretofore resilient materials formed of rubber or its compounds, natural or synthetic resins, gums or balsams, cellulose, and the like, have been reinforced to increase their tensile strength, by forcing the resilient material, while in a fluid, plastic, or semi-plastic state, into the body, or into contact with the warp or woof threads or wires of a woven fabric; or alternatively, by covering the surface or surfaces of such resilient material with a woven fabric. This practice, while it serves to increase the tensile strength of the resilient material, lessens the natural resiliency of the material, and does not prevent the wearing or transverse sawing action of the warp and woof threads or wires upon each other, which is particularly noticeable in bicycle and automobile tires and shoes.

In order to overcome the objections stated, I have devised a new method of treatment and produced a new article of manufacture. In my improved method, the warp and woof threads or wires or both of them, are primarily coated with a material or materials, which when treated in the usual manner, as by the action of chemicals, heating or vulcanizing, form resilient bodies, and such warp or woof threads or wires or both of them, consolidated by weaving, overlying or otherwise, to form a fabric, which fabric if desired, may be given a coating of resilient material on one or more of its surfaces.

The product of my improved method is a material which may be given any desired form, and in which the usual degree of resiliency of the material used is not affected, whereas the tensile strength is increased to correspond to the tensile strength of the reinforcing threads or wires employed.

The accompanying drawings will serve to illustrate my invention, in which Figure 1 is a vertical section diagrammatic in character, and intended to represent the means

employed for applying two coatings of dissimilar resilient material to warp and woof threads or wires, and then drying. Fig. 2 is a similar view, showing the apparatus employed for applying one coating, then chemically acting upon the coating, and then drying. Fig. 3 is a transverse section through one of the drying tanks and illustrates different sections which may be given to the warp and woof threads or wires to be coated and as located in the resilient coating material. Fig. 4 is a vertical elevation and partial section, illustrative of a thread or wire having two resilient coatings. Fig. 5 is a similar view illustrating a thread or wire having one resilient coating. Fig. 6 is a plan view illustrative of a fabric composed of coated and intermingled warp and woof threads or wires. Fig. 7 is a section taken on the line VII—VII of Fig. 6. Fig. 8 is a vertical section corresponding to Figs. 1 and 2, showing the method of applying a single resilient coating and drying. Fig. 9 is a section through a fabric having the warp and woof threads or wires, covered or interwoven, with surfaces of resilient material.

Referring to the drawings. A indicates a thread or wire to be formed of any suitable material, such as vegetable or animal fiber, a metal or compound, or alloys of metals, and of any cross-section (see Fig. 3) as may be desired. Surrounding the thread or wire is a covering B (shown as circular in section) which may be applied as a single layer, as shown in Fig. 5, or as two layers, as shown at B—B' in Fig. 4. The covering B may be of any resilient material, such for instance, rubber or its compounds, natural or synthetic resins, gums and balsams, cellulose, condensation products of phenol and formaldehyde, and the like. I do not limit myself to any particular material. The material may consist of resilient material, or two or more resilient materials; it may be formed of one layer or two or more layers; one of these layers may be of high resiliency and the other of lower resiliency. The cross-section of the covering B may be circular, as shown, or conform to the cross-section of the thread or wire as indicated in dotted lines, Fig. 3.

I do not limit myself in any wise to any

method of applying the covering to the thread or wire. The covering may be applied by drawing the thread or wire through a mass of plastic material, as illustrated at 5 C, Fig. 8, or through separate masses of plastic material as indicated at C and D, Fig. 1, or through a mass of plastic material and a chemical which coacts with the plastic material, as indicated at C and E, Fig. 2. 10 In Figs. 1, 2 and 3, the coated thread or wire is shown as carried through a drying apparatus indicated at F. As the character and method of treatment of the resilient materials above specified is well known and 15 forms no part of my invention, I will not enter into any description of the treatment to which such materials are subjected to render them plastic or to harden, dry or vulcanize them.

20 Instead of applying the resilient material as illustrated, by drawing the thread or wire through plastic masses and through a die J of the required size or shape, or through chemical substances and heating and dry- 25 ing apparatus, I may, in accordance with methods now known in the art, otherwise apply the plastic material, as for instance by causing the thread or wire to pass through rolls disposed to form a plastic 30 mass around the surface of the thread or wire, or by winding the thread or wire with a resilient tape, or otherwise; it being im- 35 material, so far as my invention is concerned, how the plastic resilient material is applied to the thread or wire, so long as the thread or wire is covered.

The thread or wire, provided with a plastic covering, as above described, is then interwoven to form a fabric, as illustrated in 40 Figs. 6 and 7, where G indicates the warp threads or wires, and H the woof threads or wires. I do not limit myself in any wise to the disposition of the warp and woof threads or wires as regards each other; they may 45 be intermingled in any known way. Further, the fabric may consist entirely of one character of covered thread or wire, as for instance woof threads or wires, overlying, crossed, mingled, intermixed, or bearing any 50 relation to each other. I have only illustrated one method of intermingling threads or wires, *i. e.*, Figs. 6 and 7. Manifestly any arrangement of threads or wires may be employed. Warp or woof threads or wires 55 may be employed, as will be readily understood by those familiar with the art of producing fabrics. In the drawings I have shown the threads or wires made of a single strand. Manifestly they may be made up 60 of a number of strands, laced, braided or otherwise.

After producing the body of the fabric, as for instance with warp and woof threads or wires, I may cover the fabric by applying 65 to its surfaces or forcing through the

body thereof, a coating I of resilient material, corresponding in resiliency to that applied to the threads or wires, or differing therefrom so far as resiliency is concerned.

It will be seen from the above description, that where the threads or wires are covered by a resilient material, and are then crossed or otherwise overlie each other, as in weaving, the threads or wires do not come in contact, but only the coverings, which being of resilient material, prevent cutting or sawing of the threads or wires which give tensile strength to the material. Further, that as the threads or wires are embodied in the resilient material, they are not liable to be injured by water, oxidation, etc.; and owing to the resiliency of the coverings of the threads or wires, the resiliency of the material as a whole is preserved, while the tensile strength of the fabric is considerably greater than would be the case if it were formed wholly of the resilient material.

Having thus described my invention, I claim:

1. A method of reinforcing resilient material, which consists in weaving or intermixing threads coated with a homogeneous resilient material to form a fabric, then applying to the fabric on one or more of its surfaces a further body of resilient material.

2. A method of reinforcing resilient material, which consists in primarily coating reinforcing threads or wires with a homogeneous, dry and resilient material, then weaving or intermixing the threads so coated to form a fabric, then applying to the fabric on one or more of its surfaces a further body of resilient material.

3. A method of reinforcing resilient material, which consists in weaving or intermixing threads coated with a homogeneous resilient material and in an amount sufficient when such threads are woven or intermixed, to prevent the contact of threads or movement of one thread over another, then applying to the fabric on one or more of its surfaces, a further body of resilient material.

4. As a new article of manufacture, a fabric consisting of interlaced threads, each thread separately covered with a material which after drying is resilient and homogeneous, and a coating of corresponding resilient and homogeneous material applied to the surface or surfaces of such fabric.

5. As a new article of manufacture, a fabric consisting of interwoven threads, each thread covered with a material applied before weaving, which is homogeneous and resilient after drying, and the woven and covered threads impregnated with a corresponding homogeneous and resilient material, whereby one or more surfaces of the fabric are covered.

6. As a new article of manufacture, a fabric having each thread separately en-

veloped in a coating of a material which is homogeneous and resilient after drying, and said coated threads interwoven to lie in juxtaposition but not cemented to each other, 5 and such fabric impregnated with a corresponding material which coats and consolidates the fabric into a fabric which has approximately the resiliency of the coating

material with approximately the tensile strength of the interwoven threads. 10

In testimony whereof, I affix my signature, in the presence of two witnesses.

EMIL WEINHEIM.
